US0D1109267S

(12) **United States Design Patent** (10) **Patent No.:** **US D1,109,267 S**
(45) **Date of Patent:** **** Jan. 13, 2026**

(54) **PADDLE**

(71) Applicant: **Selkirk Sport, LLC**, Coeur d'Alene, ID (US)

(72) Inventors: **Jacob Blayne Raniere**, Post Falls, ID (US); **Robert James Barnes**, Hayden, ID (US)

(73) Assignee: **Selkirk Sport, LLC**, Coeur d'Alene, ID (US)

(**) Term: **15 Years**

(21) Appl. No.: **29/987,471**

(22) Filed: **Jan. 23, 2025**

Related U.S. Application Data

(63) Continuation of application No. 29/911,112, filed on Aug. 29, 2023, now Pat. No. Des. 1,072,983.

(57) **CLAIM**

The ornamental design for a paddle, as shown and described.

DESCRIPTION

FIG. 1 is a top, front, right-side perspective view of a paddle;

FIG. 2 is a front view thereof;

FIG. 3 is a back view thereof;

FIG. 4 is a right-side view thereof;

FIG. 5 is a left-side view thereof;

FIG. 6 is a top view thereof; and,

FIG. 7 is a bottom view thereof.

1 Claim, 7 Drawing Sheets
